UNITED STATES PATENT OFFICE.

THOMAS JAMES LITTLE, JR., OF WOODBURY, NEW JERSEY, ASSIGNOR TO WELSBACK LIGHT COMPANY, OF GLOUCESTER CITY, NEW JERSEY, A CORPORATION OF NEW JERSEY.

SPRING-RING SHADE-HOLDER.

1,090,635.

Specification of Letters Patent. Patented Mar. 17, 1914.

Application filed July 16, 1912, Serial No. 709,776. Renewed December 15, 1913. Serial No. 806,882.

To all whom it may concern:

Be it known that I, THOMAS J. LITTLE, Jr., a resident of Woodbury, in the county of Gloucester and State of New Jersey, have 5 invented a new and useful Improvement in Spring-Ring Shade-Holders, of which the following is a full, clear, and exact description, reference being had to the accompanying drawings, forming part of this specification, in which—

Figure 1 is a bottom plan view of an inverted incandescent gas burner provided with my improved spring ring holder; and Figs. 2 and 3 are detail views hereinafter 15 referred to.

My invention relates to the class of spring ring holders for globes or shades, and especially to the slot in the flange of the burner for receiving the supporting loop at the 20 opposite side of the spring ring holder from that of the handles.

The object of the invention is to provide a very simple and efficient means for holding the wire loop in this slot.

25 To that end the invention consists in so shaping and arranging the loop and walls of the slot relatively to each other through which the loop extends, that the loop may be allowed movement within the slot during 30 operating (contracting and expanding), while at the same time removal or slipping out of the loop from the slot is prevented when the parts are in their normal arrangement and relation to each other; it also 35 consists in the form shown in providing the slot with a central restricted portion which, when brought to position, will retain the loop or U-shaped projection of the spring ring in position.

40 In the drawing, 2 represents an inverted incandescent gas burner having the usual depending flange 3. This flange is preferably grooved or recessed and receives the spring ring holder 4. This is formed of 45 spring wire in one piece with a U-shaped supporting portion 5 at one side, which projects through a slot 6 in the burner flange. This slot is provided with a central restricted portion 7, shown as in the form of a 50 holding member, which extends into or across the slot. This restricted portion is preferably formed in the cutting of the slot and may be bent back for insertion of the loop and then bent into position to restrict 55 the central portion of the slot and hold the

U-shaped projection or loop of the spring ring holder.

The spring ring holder may be of any desired form and may act either by contraction or expansion. In the form shown, it normally expands and its projecting handles 8, 8, pass through slots 9, 9, having hooks 10, to receive them when pressed into holding position. I have shown the wire as supported on swinging side loops or arms 10' 65 within the burner, though this may or may not be so, as desired.

The advantages of the invention result from the use of the restricted central portion of the slot for the U-shaped projection 70 of the spring ring holder. The device is easily and cheaply made, as the slot may be formed and opened up to receive the U-shaped projection and the central portion then bent anywhere to contract the space 75 and retain the wire in position. In assembling, the handle portions will be slipped through their slots, the U-shaped projection will be slipped through its slot, and the prong, forming the contraction, will be then 80 bent into place, thus holding the U-shaped projection securely in position while allowing it to yield or move slightly to aid in centering the globe.

The spring ring may act by contraction 85 or expansion, the handles and slots therefor may be changed, and other changes may be made without departing from the spirit of my invention, as defined in the appended claims.

90 I claim:

1. In a shade or globe holder, an annular flange, a ring-like wire shade retaining element having a U-shaped projection adjacent its middle portion, a slot formed in said 95 annular flange through which said projection is adapted to extend, said slot being provided with a central restricted portion adapted to be positioned to retain said projection in engagement with said flange, said 100 ring-like element having its ends offset to form operating handles, and a second and elongated slot formed in said annular flange through which said handles pass to the outside of the flange; substantially as described. 105

2. In a shade or globe holder, an annular flange, a ring-like wire shade retaining element having a projection adjacent to its middle portion, the annular flange having a slot through which said projection is 110

adapted to extend, said slot being provided with a central restricted portion arranged to retain said projection in engagement with said flange, the ring-like wire retaining element having operating handles; substantially as described.

3. A shade or globe holder having an annular flange, a ring-like wire shade retaining element having a loop in its intermediate portion, there being a slot formed in the said annular flange through which the loop extends, said loop and slot being shaped to permit the loop to move freely a predetermined distance and to prevent the removal 15 of the loop when the shade retaining element is in its normal position within the shade holder; substantially as described.

4. A shade or globe holder having an annular flange, a ring-like wire shade retaining element having a loop in its intermediate portion, there being an opening formed 20 in the said annular flange through which

the loop extends, the opening being shaped to permit the loop to move a predetermined distance to prevent removal of the loop 25 when the shade retaining element is in its normal position within the shade holder; substantially as described.

5. A shade or globe holder having an annular flange, a ring-like wire shade retaining element having a loop in its intermediate portion, there being an opening formed in said annular flange through which the loop extends, and a holding member coacting with the opening to prevent the loop 30 from accidental displacement from the slot, while allowing some movement of said loop; substantially as described.

In testimony whereof, I have hereunto set my hand.

THOMAS JAMES LITTLE, JR.
